UNITED SHOE MACHINERY CORPORATION, OF PATERSON, NEW JERSEY, A
CORPORATION OF NEW JERSEY.

FASTENING-INSERTING MACHINE.

1,407,000.

Specification of Letters Patent. Patented Feb. 21, 1922.

Application filed May 17, 1920. Serial No. 381,894.

To all whom it may concern:

Be it known that we, FRED RICKS and ALBERT A. ASTON, subjects of the King of England, residing at Leicester, Leicestershire, England, have invented certain Improvements in Fastening-Inserting Machines, of which the following description, in connection with the accompanying drawings, is a specification, like reference characters on the drawings indicating like parts in the several figures.

This invention relates to fastening inserting machines, particularly to machines which comprise cutting mechanism for severing individual fastenings from fastening stock, and to the setting and adjustment of the severing means thereof. The invention will be herein described, by way of example, in its relation to the setting of the cutters of a machine for inserting screw-threaded fastenings formed from wire, machines of this type being shown in Letters Patent No. 490,621, granted January 24, 1893 on application of Louis Goddu and No. 691,354, granted January 21, 1902 on application of Louis A. Casgrain.

Heretofore in replacing worn or broken cutters in machines of the type shown in the above-mentioned patents, the adjustment of the cutters in their holders in such a manner as to ensure the proper severance of the wire without harmful contact of the cutting edges has been an operation requiring the exercise of considerable care and skill on the part of the operator and involving an appreciable amount of time for its accomplishment. Moreover, inasmuch as the adjustment of the cutters depended upon the judgment of the operator, the adjustment was often not accurately effected, in consequence of which the cutters might be injured or broken upon subsequent operation of the machine.

Objects of the invention are to facilitate the setting of the cutting devices of such machines in a manner which will enable them to be set quickly and which will eliminate the necessity for the exercise of judgment on the part of the operator, thus insuring their correct adjustment.

An important feature of the invention in its machine aspect resides in the provision

with fastening inserting mechanism comprising automatically-operated elements movable relatively to each other to permit stock to be introduced between them and to sever the stock of operator-controlled mechanism arranged to locate the elements while the machine is at rest in the relative positions occupied by them at the completion of a cutting operation. Preferably, the operator-controlled mechanism is so constructed as to move the elements invariably through the same distance and to the same positions whenever it is actuated by the operator and to maintain the elements in such positions until it is again rendered inoperative. In the illustrated construction, the operating means for the elements includes a rotary actuator having projections for actuating them and the operator-controlled mechanism comprises a member carried by a part of the operating means and arranged to effect relative movement of the elements by engagement with the actuator.

A further feature of the invention pertains to the combination with cutting mechanism comprising elements operated by means so constructed as to spring in the performance of a cutting operation of mechanism for moving said elements to facilitate the setting of the cutting devices constructed to compensate for the spring of the operating means.

The invention also comprises a method of setting or adjusting the cutters of fastening cutting and inserting machines which comprises bringing a gage into position between parts of the cutter operating mechanism so as to bring the cutter holders into the position which they should occupy at the conclusion of each cutting operation, and securing the cutters to the cutter holders while the latter are in that position.

Although the invention is herein described in its relation to a machine for inserting fastenings, it is recognized that the invention as a whole and various features thereof may be employed in connection with machines other than fastening inserting machines. It is intended, therefore, that the scope of the invention shall not be limited except as required by the claims.

Other objects and features of the inven-

tion will be apparent as the description proceeds and will be pointed out in the appended claims.

In the drawings—

5 Fig. 1 is a view in elevation of a fastening inserting machine embodying the invention, looking from the rear of the machine;

10 Fig. 2 is a view in elevation of the cutter holders mounted on the front of the machine;

15 Fig. 3 is a detail view of a portion of the operating connections for the cutter holders;

20 Fig. 4 is a view on an enlarged scale of the means for facilitating the setting of the cutters in the cutter holders; and

25 Fig. 5 is a view similar to Fig. 4 showing the parts, looking from the right in Fig. 4, and partly in cross-section.

The illustrated machine comprises a head 2 in the front of which is mounted a stud shaft 4 on which are pivoted cutter holders 6 and 8. The cutter holders 6 and 8 are 30 split at their lower sides to receive cutters 10 and 12, respectively, which are secured in adjusted position in the holders by screws 14. The cutter holders 6 and 8 are provided with rack teeth adapted for engagement 35 with teeth 16 and 18, respectively, on a gear 20. A spring 22, interposed between the cutter holder 6 and a screw plug 24 seated in the cutter holder 8, tends normally to press them apart and serves to take up any backlash in the operating connections for the cutter holders.

The gear 20 is mounted on a shaft 26 rotatable in the head 2 of the machine. An arm 28, forming part of a split casting 40 clamped on the shaft 26 by screws 30, is connected to one end of a link 32, the other end of which is joined to a lever 34 fulcrumed on a shaft 36 on the head 2. At its rear end, the lever 34 is provided with 45 an upstanding finger 38 normally interposed in the path of movement of toes 40 on an actuator cam 42 fast on the main cam shaft of the machine. The finger 38 is pivotally carried by a stud 44 in the end of the lever 50 34, the arrangement being such that the finger 38 may be swung to the right, from the position shown in Fig. 1, to remove it from the path of movement of the toes 40, thus rendering the actuator cam 42 inoperative 55 on the cutter holders. A spring 45 causes the lever 34 to move finger 38 into the path of movement of the toes on the actuator cam 42 when that finger is in operative position. The parts hereinbefore described constitute in themselves no part of the present invention, being substantially as shown and described in the patent to Casgrain No. 691,354.

It has been customary in setting the cutters in their holders to swing the finger 60

about the stud 44 into operative relation to the actuator cam 42, and then to turn the actuator cam by hand into a position in which the finger 38 is not quite at the highest part of one of the toes 40, the distance of the finger 38 from the highest part of the toe being such as to compensate, in the judgment of the operator, for the spring of the operating connections to the cutter holders in the operation of cutting a fastening from the wire. In this position of the parts, the cutters are placed in their holders with their cutting edges in contact.

In the present embodiment of the invention, there is pivoted on the stud 44 a bell-crank lever 46, one arm 48 of which has on its end a face 50 which, when the bell-crank lever is swung by a pressure of the operator's finger on a finger piece 52 on its other arm, bears on the concentric part of the cam 42 and forces the lever 34 about its fulcrum to an extent less than its movement by the toes 40 in the operation of cutting the wire by an amount corresponding to the spring of the parts of the operating 90 connections to the cutter holders 6 and 8. The stud 44 has a head 54 projecting beyond the surface of the bell-crank lever 46, and a spring 56 fast on the bell-crank lever 46 bears on the head, creating friction tending to hold the bell-crank lever in any position to which it may be turned on the stud 44. The bell-crank lever 46 is moved out of operative position when the machine is started up in consequence of the friction between the face 50 of the arm 48 and the concentric face of the actuator cam 42, the latter in its movement swinging the bell-crank lever about the stud 44.

The arm 48 of the bell-crank lever 46 is 105 cut away at 58 so as to allow the face 50 to be passed between a reduced part 60 of the finger 38 and the face of the cam 42 when the finger 38 is in operative position. The head 54 of the stud 44 is also provided with shoulders 62, with which the spring 56 contacts, thus serving as limiting stops for the movement of the lever 46 into its operative and inoperative positions.

In the use of the invention, when it is desired to install cutters in the cutter holders 6 and 8, the operator merely moves the bell-crank lever 46 from the position shown in full lines in Fig. 4 to that shown in dotted lines, and then places the cutters in the 115 holders with their cutting edges in contact. It will be apparent that by the use of the invention, the cutters may be set in their holders without the necessity of swinging the finger 38 to operative position with relation to the toes 40 of the actuator cam 42 or of turning the actuator cam. Moreover, the exercise of judgment on the part of the operator in setting the cutters is obviated, since lever 48 acts as a gage, thus insuring that the 120 125 130

cutters will always be set in proper positions.

Having thus described our invention, what we claim as new and desire to secure 5 by Letters Patent of the United States is:

1. In a machine of the class described, fastening inserting mechanism comprising elements movable relatively to each other to permit fastening stock to be introduced between them and to sever individual fastenings therefrom, means for operating said elements, and operator-controlled mechanism arranged to locate the elements while the machine is at rest in the relative positions occupied by them at the completion 10 of a severing operation.

2. In a machine of the class described, mechanism for severing fastenings from fastening stock comprising relatively movable parts, power-operated means for moving said parts to sever fastenings, and manually operable means for moving said parts to severing position.

3. In a machine of the class described, cutting mechanism comprising elements movable relatively to each other to permit fastening stock to be introduced between them and to sever individual fastenings therefrom, means for operating the elements to severing position comprising an actuator, and an operator-controlled device arranged for engagement with the actuator when the machine is at rest to move the elements to severing position.

4. In a machine of the class described, mechanism for severing fastenings from fastening stock comprising elements adapted to occupy predetermined relative positions at the end of a severing operation, means for automatically effecting relative movement of the elements to permit the fastening stock to be introduced between them and to sever the stock, and operator-controlled means constructed, when rendered operative, to effect invariable relative movement of said elements to place them in the relative positions occupied by them at the completion of a severing operation.

5. In a machine of the class described, cutting mechanism comprising elements movable relatively to each other to permit stock to be introduced between them and to sever the stock, means for operating said elements so constructed as to spring in the performance of a severing operation, and means for moving the elements while the machine is at rest to the relative positions occupied by them at the completion of a severing operation to facilitate setting the cutting mechanism, said means being constructed to compensate for the spring of the operating means.

6. In a machine of the class described, cutting mechanism comprising elements movable relatively to each other in the perform-

ance of a cutting operation, operating means for the elements including a member movable to impart movement to the elements, the movement of said member in the performance of a cutting operation being proportionally greater than that of the elements by reason of the spring of the operating means, and means for moving the elements while the machine is at rest to the position occupied by them at the end of a cutting operation.

7. The combination with fastening inserting mechanism comprising a cutter, a cutter holder in which the cutter is adjustable, and means for operating the cutter holder, 80 of a member arranged for manipulation by the operator and constructed when actuated by the operator invariably to move the cutter holder to the position which it occupies at the end of a cutting operation so as to facilitate the adjustment of the cutter in the holder.

8. In a machine of the class described, cutting mechanism comprising a cutter, a cutter holder, means for automatically moving the cutter holder to cause the cutter to perform a cutting operation, and manually operable means for reproducing the movement of the cutter holder while the machine is at rest to facilitate the setting of the cutter in its holder.

9. In a machine of the class described, cutting mechanism comprising a cutter, a cutter holder, operating means for the cutter holder including a member movable in the performance of a cutting operation through a distance proportionally greater than that traversed by the cutter holder by reason of the spring of the parts of the operating means, and means for moving said member 100 when the machine is at rest to an extent less than its movement in the performance of a cutting operation by an amount corresponding to the spring of said parts.

10. In a machine of the class described, a cutter, a cutter holder, operating means for the cutter holder including a movable member and an actuator for automatically moving the member, and operator-controlled means carried by the member for moving it 110 while the machine is at rest to impart to the holder a movement of like character to that imparted to it by the actuator in the performance of a cutting operation.

11. In a machine of the class described, a cutter, a cutter holder movable to a predetermined position in the performance of a cutting operation, operating means for the cutter holder comprising a lever and an actuator for the lever, and a member 120 movably mounted on the lever and operable on the actuator to move the cutter holder to said position when the machine is idle to facilitate setting the cutter in the holder.

12. In a machine of the class described, a

1. cutter, a cutter holder movable to a predetermined position in the performance of a cutting operation, operating means for the holder comprising a lever and a rotary cylindrical actuator having projections on its periphery for actuating the lever, and a member movably mounted on the lever and arranged for engagement with the periphery of the actuator to move the cutter holder to said position when the machine is idle to facilitate setting the cutter in the holder.
2. In a machine of the class described, a cutter, a cutter holder movable to a predetermined position in the performance of a cutting operation, operating means for the holder comprising a lever and a rotary cylindrical actuator having projections on its periphery for actuating the lever, and a member movably mounted on the lever for engagement with the periphery of the actuator to move the cutter holder to said position when the machine is idle to facilitate setting the cutter in the holder, said member being arranged to move the lever to an extent less than it is moved by the actuator by an amount corresponding to the spring of the operating means in the performance of a cutting operation.
3. In a machine of the class described, a cutter, a cutter holder movable to a predetermined position in the performance of a cutting operation, operating means for the holder comprising a lever and a rotary cylindrical actuator having projections on its periphery for actuating the lever, a member movably mounted on the lever and arranged for engagement with the periphery of the actuator to move the cutter holder to said position when the machine is idle to facilitate setting the cutter in the holder and means for normally maintaining the member in operative or inoperative positions relatively to the actuator constructed to permit the member to be moved out of engagement with the actuator upon movement of the actuator.
4. In a machine of the class described, a cutter, a cutter holder movable to a predetermined position in the performance of a cutting operation, means for automatically operating the holder, and means for manually moving the holder to said position while the machine is at rest and retaining it in said position, constructed to be rendered inoperative by operation of the machine.
5. In a machine of the class described, a cutter, a cutter holder movable to a predetermined position in the performance of a cutting operation, operating means for the holder comprising a movable member and an actuator for moving the member, and a bell-crank lever rotatably mounted on the member and arranged to move it to an extent less than it is moved by the actuator by an amount corresponding

to the spring of the operating means, said bell-crank being formed with a finger piece to facilitate its manipulation by the operator.

17. In a machine of the class described, mechanism for severing fastenings from fastening stock, operating means for the severing mechanism, and operator-controlled means for moving the severing mechanism without affecting the operative relations of the various parts of the operating means.

18. In a machine of the class described, cutting mechanism comprising elements movable relatively to each other to permit fastening stock to be introduced between them and to sever individual fastenings therefrom, means for moving the elements to severing position comprising an actuator member and a co-operating member operably connected to the cutting mechanism, and an operator controlled device arranged for engagement with one of said members when the machine is at rest to move the cutting elements to severing position.

19. In a machine of the class described, cutting mechanism comprising a pair of cutter holders, a pair of cutters carried thereby and movable with the cutter holders relatively to each other to permit fastening stock to be introduced between them and to sever fastenings therefrom, means for moving the cutters to severing position comprising an actuator and a lever operated thereby and connected to the cutting mechanism, and a manually shiftable lever arranged by its movement to move the actuator operated lever into position, when the machine is at rest, to move the cutter holders to severing position.

20. In a machine of the class described, a cutter, a cutter holder, operating means for the cutter holder comprising a lever and an actuator for the lever operable to move the cutter holder to a predetermined position in the performance of the cutting operations, and a second lever operable to move the cutter holder to said predetermined position when the machine is at rest to facilitate setting the cutters in the holders.

21. That method of adjusting co-operating tools of a machine which comprises introducing a gage between relatively movable parts of a machine in such a manner as to hold the tool holders in the position which they should occupy at the conclusion of an operation and securing the tools to the holders in operative relation while the holders are held in that position.

22. That method of setting the cutting mechanism of a machine which comprises bringing a gage member into position between a movable portion of the cutter actuating mechanism and a part of the machine which occupies a fixed position so as

to bring the cutter holders of the machine into the position which they should occupy at the conclusion of a cutting operation, and securing the cutters to the holders in correct 5 cutting relation while the holders are so positioned.

23. That method of setting the cutters of a machine which comprises introducing a gage between relatively movable parts of 10 the cutter operating mechanism to bring the cutter holders into the position which they should occupy at the conclusion of a cutting operation and securing the cutters to the holders in cutting relation while the cutters 15 are thus held in that position.

24. That method of setting the cutting

mechanism of a machine which comprises bringing a gage member into position between a movable portion of the cutter actuating mechanism and a part of the machine which occupies a fixed position so as to bring the cutter holders of the machine into the position which they should occupy at the conclusion of a cutting operation, and securing the cutters to the holders with their 20 cutting edges in contacting relation while the holders are so positioned.

In testimony whereof we have signed our names to this specification.

FRED RICKS,
ALBERT AMOS ASTON.
